UNITED STATES PATENT OFFICE.

HENRY W. FRENCH, OF CHICAGO, ILLINOIS.

CLAMP.

Application filed May 16, 1921. Serial No. 469,812.

To all whom it may concern:

Be it known that I, HENRY W. FRENCH, a citizen of the United States, and a resident of the city of Chicago, county of Cook, and State of Illinois, have invented certain new and useful Improvements in Clamps, of which the following is a specification.

This invention relates to a novel clamp which is particularly adapted for securing wind deflectors to wind shields of automobiles or the like and which will adjust itself to supports of different sizes and configuration.

The device is particularly suitable for use in connection with a glass wind deflector supporting clamp of the character disclosed in my co-pending application, Serial No. 376,853, filed April 26, 1920, but the device may be utilized in many other situations.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevation of part of the wind shield frame and a glass wind deflector showing my invention in operative position;

Fig. 2 is a longitudinal sectional view of the clamp;

Fig. 3 is a detail view of the angular supporting jaw;

Fig. 4 is a top view of the major jaw of the clamp; and,

Fig. 5 is a sectional detail view on line 5—5 of Fig. 4.

The clamp broadly consists of an angular plate 1, which is preferably cast with an elongated smooth opening, through which is inserted a threaded bolt 3. A washer 4 interposed between the underside of the bolt head and the outer surface of the plate 1 to take up wear. An adjusting bolt 5 is tapped through the plate 1 preferably at right angles to the bolt 3, and engages a threaded bore 6 in said plate.

The bolt 3 is preferably threaded into a socket 7 in a jaw 8 of the clamp, the jaw 8 being movable longitudinally of the plate 1 as shown.

The jaw 8 is preferably cast with an elongated opening 9, similar to the open-

ing 4 in plate 1, and a bolt 10, threaded on its inner end, inserted through said opening and engaging a threaded bore in a jaw 11. A washer 12 is preferably interposed between the head of the bolt 10 and the outer face of the jaw 8 to take up wear when the bolt 10 is rocked in the opening 9. The head 17 of the jaw 8 may be provided with teeth or ribs 11' if desired.

Each of the jaws 8 and 11 are provided near its lower inner end with opposite preferably semi-circular grooves 13 and 14 which engage any desired object, and which are shown as applied to a rod 15 attached to a wind deflector so as to clamp said rod therebetween to permit rotation of the rod in the clamp, but to prevent longitudinal movement of said rod with respect to said clamp. When used in connection with a wind shield deflector two of the clamps are ordinarily required for securing same in position.

The jaw 8 is provided on its inner face with an inclined shoulder 16 as shown and with a bearing surface 17. The jaw 11 has an offset portion 18 and the plate 1 is provided with a flange 19. These bearing members are adjustable to engage any desired object 20; the object shown being a fragment of a wind shield frame.

In operation the clamp is easily and quickly applied by loosening the bolt 10 and partially rotating the jaw 11 and adjusting the bolts 3 and 5 as desired. The clamp is then applied to the desired objects which it is desired to secure in position and fastened by tightening the various adjusting bolts.

An important and practical feature of the clamp is its capacity for accommodating objects of different sizes, that is, instead of engaging a large object between the plate 1 and the inner ends of jaws 8 and 11, and a smaller object between the outer jaws, the inner and outer jaws of the clamp will readily engage objects of large size in the inner jaws and of small size in the outer jaws, and vice versa, etc., and readily adjust itself to varying sizes of objects engaged.

It is also evident that the construction is such that the clamp may be large or small to suit different purposes but regardless of variations in size will adjust itself to the size of the objects engaged. The various mem-

bers of the clamp are preferably cast and the elongated openings are formed during the casting operation.

When the device is in position and the adjusting bolt tightened the clamp provides a strong and reliable support. It can be cheaply and quickly manufactured and provides a neat and efficient, and adjustable device.

10 While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

15 Having described my invention, what I claim is new and desire to secure by Letters Patent, is:—

1. A device of the character described comprising a base member; a clamping jaw longitudinally and perpendicularly adjustable with respect to said base member; and a second jaw adjustably connected to said first jaw and cooperating with said base member to form a clamp.

2. A device of the character described comprising a base member; a clamping jaw longitudinally and perpendicularly adjustable with respect to said base member; a second jaw adjustably connected to said first jaw and cooperating with said base member to form a clamp, the outer ends of said jaws forming other clamping jaws.

3. A device of the character described comprising a base member having turned ends, there being a slot in said base member; a member extending through said slot and having a jaw adjustably connected thereto there being a slot in said jaw; means for adjusting said clamping jaw longitudinally of said base member; a member mounted in said slot; and a second jaw adjustably connected to said member.

4. A device of the character described comprising a base member having turned ends, there being a slot in said base member;

a member extending through said slot and having a jaw adjustably connected thereto, there being a slot in said jaw; means for adjusting said clamping jaw longitudinally of said base member; a member mounted in said slot; and a second jaw adjustably connected to said member, the outer ends of said jaws forming other clamping jaws.

5. In a device of the character described, comprising an angular supporting member; an aperture in said supporting member; a bolt movably secured in said aperture and threaded at its inner end; a second bolt threaded through said supporting member and disposed at an angle to said first bolt; a jaw having a threaded socket for engagement with said movable bolt; a second jaw movably secured to said first jaw; and means for adjustably accommodating said supporting member and said jaws to engage objects of the same or different sizes and shapes.

6. In a device of the character described comprising an angular supporting member; an elongated aperture in said supporting member; a bolt extending through said aperture movable longitudinally with relation to said supporting member, said bolt having a head engaging the outer surface of said supporting member, and having threads on its inner end; a threaded bolt tapped through said supporting member at an angle to said movable bolt; a jaw having a threaded socket engaged by the threaded end of said bolt; an elongated aperture in said jaw; a bolt extending through said aperture and being movable longitudinally of said jaw, having a head engaging the outer face of said jaw, the inner end thereof being threaded; a second jaw having a threaded bore for the reception of the threaded end of said bolt; and gripping members at opposite ends of said jaws for adjustably engaging objects of the same or different sizes and shapes.

In testimony whereof I have signed my name to this specification in the presence of two subscribing witnesses.

HENRY W. FRENCH.
